UNITED STATES PATENT OFFICE.

BLUFORD W. BROCKETT, OF CLEVELAND HEIGHTS VILLAGE, OHIO, ASSIGNEE, BY DIRECT AND MESNE ASSIGNMENTS, OF ONE-HALF TO THE AMERICAN LAUNDRY MACHINERY COMPANY, OF NORWOOD, OHIO, A CORPORATION OF OHIO, AND ONE-HALF TO METROPOLITAN TRUST COMPANY, TRUSTEE, OF NEW YORK, N. Y., A CORPORATION OF NEW YORK.

GARMENT PRESS.

Application filed June 19, 1920. Serial No. 390,170.

To all whom it may concern:

Be it known that I, BLUFORD W. BROCKETT, a citizen of the United States, residing at Cleveland Heights Village, in the county of Cuyahoga and State of Ohio, have invented certain new and useful Improvements in Garment Presses, of which the following is a specification.

This invention relates to the class of laundry machines and more especially to improvements in garment presses.

The objects of my invention are to provide a buck or garment supporting member which is more efficiently adapted for proper distribution of steam and air to and through the buck; to provide means for equalizing the distribution of steam through the buck, preparatory to pressing the garment; and to provide means for equalizing the distribution of air through the buck for the purpose of dispelling the steam from the buck as well as from the garment after the pressing operation.

Other objects of the invention will appear from the following detailed description and claims when considered in connection with the accompanying drawings.

Fig. 1 is an end elevation of my improved machine; Fig. 2 is a front elevation thereof; Fig. 3 is a longitudinal vertical section taken through the buck; Fig. 4 is a cross section taken on line *c-c*, Fig. 3; Fig. 5 is a section taken on line *a-a*, Fig. 3; Fig. 6 is a section taken on line *b-b*, Fig. 3; Fig. 7 is a plan view of the buck with parts broken away to show my improvement of the buck in detail; and Fig. 8 is an enlarged transverse section through the buck.

The frame 1 supports the work table 2 and also the buck or garment supporting member 3. The presser head 4 is swiveled at the point 5 on the forward end of an overhanging arm 6 which is rockably mounted at 7 upon an upwardly extending arm of the supporting frame 1. The arm 6 carries a counterweight 8 at its rear end. The spring 9 which extends between the arm 6 and the base portion of the supporting frame, as clearly indicated in Fig. 1, normally tends to open the presser head 4, as is well known in the art. The presser head is closed by

pressing upon treadle 10 which is mounted upon the base portion of the supporting frame and which operates through the rod 14 and the bell crank lever 12 which is pivotally mounted at 13 upon the frame. Bars 15 are pivotally connected at 16 with the end of the bell crank lever 12 and have pivotal connection at their other ends 16^a with the toggle lever mechanism which includes 60 the links 17 and 18. The link 17 is pivotally mounted upon the base portion of the machine frame, while the link 18 has pivotal connection at 20 with the overhanging arm 6. The link 18 may be adjusted so as 65 to increase or decrease the length of this lever connection and at the same time increase or diminish the tension upon the spring 19, the arrangement of which will be clearly understood from Fig. 1. Means is 70 provided as indicated at 21 for locking the link 18 in the position to which it is adjusted, this mechanism being more fully described in the patent to Cooper No. 1,332,711 of March 2, 1920. A rod 22 which is pivotally connected at 23 to the link 17 extends 75 between the bars 15 and has pivotal connection therewith, as indicated at 24. The nut 25 which may be set at different positions upon the end of the rod 22 serves as a stop 80 for limiting the movement of the toggle lever mechanism. This mechanism being old in the art will not be here described at any more length.

The presser head is closed by means of the handle 26, and any suitable means might be adopted for supplying steam to the presser head as for instance through the pipe 27. This being an old practice in the art, a detailed description thereof will not be given. 85

The buck or garment supporting member comprises the lower plate 29, along the longitudinal marginal portions of which there are provided channels 30 for the distribution of steam and air therealong, as will be later explained. Strips 31 of suitable material, as for instance metal, are secured in any suitable manner, as for instance by means of screws 32, to the marginal portions of the plate 29, and these strips 31 are so shaped 100 and so arranged that they overhang the channels 30. As will be seen from Fig. 7

of the drawing, strips 31 are narrowed towards their ends and bear such relation to the channels 30 that the cross section of the slots 30^a formed thereby increases from a point substantially midway of the length of the buck toward the end portions thereof. The purpose of this arrangement will appear later. It will be also observed from the figures of the drawing that the strips 31 are so seated upon the plate 29 that their upper surfaces are flush with the upper face of the plate. Suitable layers of padding 35 cover the plate member 29 and are in turn covered by the oilcloth 36, the marginal portions of which are turned in under the padding 35. Superimposed upon the layer of oilcloth just referred to is a layer of wire fabric 37 which provides space between the underlying layers and the layer of padding 39 which overlies the same. Strips of oilcloth 38 extend along the inner face of the padding 39 and overlap the marginal portions of the wire fabric 37. The outer covering 40 is the ordinary muslin, duck or other suitable fabric which is pervious to air and steam. These layers are secured in proper position upon the buck by means of the cord 41, as is well known in the art.

The purpose of the particular arrangement of the layers just referred to will appear from the description which is to follow.

The buck or garment supporting member is provided with a steam chamber 42 which has communication through the ports 46 and 48 with the channel 43. This channel 43, which is formed in the extension 44 upon the lower face of the plate 29, extends transversely across the buck and communicates through ports 42^a with channels 30 at points substantially midway of the length thereof, and thus supplies steam to the underside of strips 31. The valve 47 which controls the passage of the steam over the path just described is actuated by means of the rod 49, the lower portion of which is enclosed in the housing 50 which is attached to the under side of the steam chamber. As will be seen from Fig. 1, the valve rod 49 is actuated by means of treadle 51 which is pivotally mounted upon the lower portion of the frame. Steam is supplied to the chamber 42 through the inlet 52 and a drain 53 is provided for the condensed steam.

A fan 54 of any suitable type is provided for supplying air through a pipe connection to the channels 30 and thus to the under side of the deflecting strips 31. This pipe connection which is jointed at 55 surrounds the rod 61 for operating the valve 60 which is normally seated in closed position as shown in Fig. 3. This valve is operated by means of treadle 62 which is mounted upon the supporting frame at 59. The treadle 62 which forms one arm of a bell-crank lever, is operatively connected with the connecting

rod 60^a. Rod 60^a is connected with one arm of bell-crank lever 63, which is mounted upon shaft 64 supported in suitable bearings 65 on the frame. The other arm of the bell-crank lever 63 has a forked arm 37 which engages a spring 68 arranged below the collar 69 on valve rod 61. A stop or rest 70 is provided on the end of treadle lever 62 for engagement with the floor. As will be seen from Fig. 6 of the drawing, the main air pipe 52 has connection with the pipes 57 for distribution of the air to the ports 58 which have communication through ports 58^a with the channels 30 at points substantially midway of the length thereof. The upper ends of the pipes 57 are threaded in the underside of the buck, as shown.

Thus it will be seen that upon bringing the presser head to closed position with relation to the buck, steam can be supplied to the presser head in the usual manner and also to the buck through slots 30^a through operation of the mechanism just described. By virtue of the particular arrangement of these slots the steam will be more uniformly distributed through the padding on the buck. This is so because of the fact that the slots are more restricted at the points of supply of steam, whereas, the slots are of larger cross section at points removed from the point of steam supply. In other words, the plate 31 acts as a deflecting means for distributing part of the steam along the buck before it is allowed to pass through the slots. In this way the distribution of steam is equalized throughout the extent of the garment supporting member.

Then because of the particular structure and arrangement of the padding on the buck the steam will pass directly through the upper portion of the padding without passing through the lower portion thereof. This is made possible because of the impossibility of the steam to penetrate through the oilcloth which covers the lower layers of the padding. The strips of oilcloth 38 serve as a means for deflecting the steam after its passage through the slots 30^a and directing it through the space provided by the wire mesh 37. They also serve to shield or protect those portions of the upper or pervious layer of padding from the steam and prevent either steam or air from passing through the pervious layers of padding except over the ordinary central pressing area thereof. As a result of this arrangement the benefit of the lower padding layers is realized as a cushioning means without these layers being saturated with steam and therefore without the subsequent deterioration thereof. If the steam were allowed to penetrate the lower layers of the padding they would soon become soggy, which would be decidedly objectionable. Then, too, with the present arrangement it is neces-

sary to remove steam only from the upper layer of padding upon completion of the pressing operation, which means a saving in point of time.

5. The layers of oilcloth serve as a deflecting means in connection with the air as well as for steam, and likewise the plates 31 serve to deflect and distribute the air to better advantage throughout the extent of the 10 buck. The air upon being forced through the pipes 57 is caused by the plates 31 to be deflected and distributed through the slots 30^a. Whereupon it is further deflected by the strips of oilcloth 38 15 and caused to pass through the wire mesh and eventually through the upper layer of padding to the garment supported thereon. This air is turned on upon completion of the pressing operation when it is 20 desired to dispel the steam both from the buck and from the garment. As will be understood, steam is more readily removed while still in a mobile state, and with my arrangement a high degree of efficiency is 25 attained in this respect. Not only is the efficiency of such a device improved by my structure in point of economy of time, but also from the standpoint of prolonging the life of the padding on the buck.

30. It is to be understood that in my device the steam might also be removed from the padding by sucking it out through the slots and the other connections above described for the air, instead of blowing it 35 out in the manner already referred to.

Other advantages resulting from my device will readily suggest themselves to those who are familiar with the art.

What I claim is:

40. 1. In a garment press, a garment supporting member, a body of padding on said member, and means for passing a gaseous medium through only the upper portion of said padding.

45. 2. In a garment press, the combination of a garment supporting member having a lower body of padding that is impervious to steam, an upper body of padding that is pervious to steam, and means for passing steam between said bodies of padding.

50. 3. In a garment press, the combination of a garment supporting member having a lower body of padding that is impervious to steam, an upper body of padding that is pervious to steam, steam pervious means for spacing said bodies of padding, and means for passing steam between said bodies of padding.

55. 4. In a garment press, the combination of a garment supporting member having a lower body of padding that is impervious to steam, an upper body of padding that is pervious to steam, and means for conducting steam from a point below said member to a level above said impervious body

of padding and for directing and distributing the steam between said bodies of padding.

5. In a garment press, the combination of a garment supporting member having a 70 lower body of padding that is impervious to air, an upper body of padding that is pervious to air, and means for passing air between said bodies of padding.

6. In a garment press, the combination 75 of a garment supporting member having a lower body of padding that is impervious to air, an upper body of padding that is pervious to air, air-pervious means for spacing said bodies of padding, and means for 80 passing air between said bodies of padding.

7. In a garment press, the combination of a garment supporting member having a lower body of padding that is impervious 85 to air, an upper body of padding that is pervious to air, and means for conducting air from a point below said member to a level above said impervious body of padding and for directing and distributing the 90 air between said bodies of padding.

8. In a garment press, the combination of a garment supporting member having a lower body of padding impervious to steam and air, an upper body of padding pervious 95 to steam and air, and means for passing steam or air between said bodies of padding.

9. In a garment press, the combination of a garment supporting member having a lower body of padding impervious to steam and air, an upper body of padding pervious 100 to steam and air, means pervious to steam and air for spacing said bodies of padding, and means for passing steam or air between said bodies of padding.

10. In a garment press, the combination of a garment supporting member having a lower body of padding impervious to steam and air, an upper body of padding pervious 110 to steam and air, and means for conducting steam or air from a point below said member to a level above said impervious body of padding and for directing and distributing the steam or air between said bodies of padding.

11. In a garment press, the combination of a garment supporting member having a lower body of padding that is impervious to steam, an upper body of padding that is pervious to steam, means for passing steam between said bodies of padding, and means along the marginal portions of the garment supporting member for directing the steam along its path.

12. In a garment press, the combination of a garment supporting member having a lower body of padding that is impervious to air, an upper body of padding that is pervious to air, means for passing air between said bodies of padding, and means along the 125

marginal portions of the garment supporting member for directing the air along its path.

13. In a garment press, the combination of a garment supporting member having a lower body of padding that is impervious to air and steam, an upper body of padding that is pervious to air and steam, air-pervious means for spacing said bodies of padding, means for passing air and steam between said bodies of padding, and means along the marginal portion of the garment supporting member for directing the steam and air along their paths.

14. In a garment press, the combination of a garment supporting member having a base portion supporting a body of padding that is impervious to air and steam and an upper body of padding that is pervious to air and steam, said base portion being provided with a slot which forms part of the channel for the air or steam through the garment supporting member, and means between the slot and the upper body of padding for directing the air or steam along its path.

15. In a garment press, the combination of a garment supporting member having a base portion supporting a body of padding that is impervious to air and steam and an upper body of padding that is pervious to air and steam, said base portion being provided with a marginal slot which forms part of the circuit of the air or steam through the garment supporting member, and means between the slot and the upper body of padding for directing the air or steam around the edge of the impervious padding body to the pervious body.

16. In a garment press, the combination of a padded garment supporting member provided with an extended channel, a deflecting means overhanging said channel in such a manner as to form a graduated slot leading therefrom, and means providing communication with said channel at a point of restricted cross-section of said slot and on the side of said slot opposite the padding.

17. In a garment press, the combination of a garment supporting member, a relatively movable ironing member, the garment supporting member having a lower body of padding that is impervious to steam and air and an upper body of padding that is pervious to steam and air, and means for supplying steam to the plane of contact between said members.

18. In a garment press, the combination of a garment supporting member, a relatively movable ironing member, the garment supporting member having a lower body of padding that is impervious to steam and air and an upper body of padding that is pervious to steam and air, means for supplying

steam to the plane of contact between said members, and means providing for passage of air between said bodies of padding.

19. A garment press, comprising a garment support, padding thereon having a portion pervious to the passage of a gaseous medium, and means impervious to said gaseous medium extending from the edge of the garment support toward the pressing area of said padding and thereby preventing the flow of gaseous medium through the edge portion of the padding.

20. In a garment press, a garment supporting member having an imperforate upper heat conducting wall and a heating chamber below and bounded by said wall, said member having a padding resting on said wall and impervious to steam or air, and a padding overlying said first-named padding which is pervious to steam or air, the arrangement being such that the heat of said heating chamber is transmitted directly through said wall to said paddings.

21. In a garment press, a garment supporting member having a cover of pervious padding, means for supplying steam to said padding, means for supplying air to a level within the upper portion of said padding, and means for distributing said air along said level through the padding.

22. In a garment press, the combination of a garment supporting member including a support having a covering of padding that is pervious to steam and air, means for supplying steam to said padding, means for supplying air to points in the marginal portions of said padding, and air-distributing means extending from said point of air supply within the thickness of said padding.

23. A garment press, including a work support provided with a yielding padding having its lower portion impervious to a gaseous medium and its upper portion pervious thereto, and means for causing the flow of a gaseous medium through the pervious portion of the padding.

24. In a garment press, a garment support, a pad thereon having a lower portion impervious to steam and lying adjacent the support and an overlying pervious portion, and means for passing steam around said impervious portion and supplying it to said pervious portion.

25. A garment press, including a work support, a pad thereon having a lower portion incapable of absorbing moisture, and an upper portion pervious to steam, and means for supplying steam to said padding for distribution to a garment on said support.

In testimony whereof I affix my signature.

BLUFORD W. BROCKETT.

4564466

Certificate of Correction.

It is hereby certified that in Letters Patent No. 1,564,466, granted December 8, 1925, upon the application of Bluford W. Brockett, of Cleveland Heights Village, Ohio, for an improvement in "Garment Presses," an error appears in the printed specification requiring correction as follows: Page 4, line 33, claim 15, for the words "circuit of" read *channel for*; and that the said Letters Patent should be read with this correction therein that the same may conform to the record of the case in the Patent Office.

Signed and sealed this 2d day of March, A. D. 1926.

[**SEAL.**]

M. J. MOORE,
Acting Commissioner of Patents.
